Primary Examiner — Catheri Oliver-Garcia(74) Attorney, Agent, or Firm — Gottlieb, Rackman & Reisman, PC(57) CLAIM

The ornamental design for a holster, as shown and described.

DESCRIPTION

FIG. 1 is a front perspective view of a holster showing my new design;

FIG. 2 is a first side view thereof;

FIG. 3 is a second side view thereof;

FIG. 4 is a third side view thereof;

FIG. 5 is a fourth side view thereof;

FIG. 6 is a top view thereof; and,

FIG. 7 is a bottom view thereof.

The broken lines shown in the drawings are included for the purpose of illustrating portions of the article that form no part of the claimed design.

1 Claim, 7 Drawing Sheets(56)
